UNITED STATES PATENT OFFICE.

REUBEN JONES, OF ATLANTA, GEORGIA, ASSIGNOR OF THREE-FOURTHS TO
CHARLES A. SINDALL, OF SAME PLACE.

CAR-COUPING.

SPECIFICATION forming part of Letters Patent No. 350,062, dated September 28, 1886.

Application filed August 23, 1886. Serial No. 211,684. (No model.)

To all whom it may concern:

Be it known that I, REUBEN JONES, a citizen of the United States, residing at Atlanta, in the county of Fulton and State of Georgia, 5 have invented a new and useful Car-Coupling; and I do hereby declare the following to be a full, clear, and exact description of the invention, such as will enable others skilled in the art to which it appertains to make and use the 10 same, reference being had to the accompanying drawings, and to letters or figures of reference marked thereon, which form a part of this specification.

This invention relates to the class of car-couplings that have a link and a pin lifter, and 15 has especial reference to the improvement in car-couplings for which Letters Patent of the United States were granted me on the 25th day of May, 1886, bearing No. 342,517, and also to 20 an invention contained in an application filed by me on the 2d day of July, 1886, No. 206,992, series of 1880; and it principally consists in mechanism for operating the link and pin lifter therein described.

25 In the accompanying drawings, Figure I is a perspective of a draw-head. Fig. II is a vertical longitudinal section through the draw-head with the pin raised. Fig. III is a detail showing the shaft which pivots the link-lifter. 30 Fig. IV is a detail showing the shaft of the pin-lifter. Fig. V is a section of a portion of the draw-head, showing the inside of the lug 17.

In the figures, 1 is a draw-head. 2 is a link-lifter pivoted in the neck of the 35 draw-head by the shaft 3, which has an upwardly-projecting crank, 4.

5 is the pin, and 6 the pin lifter, connected thereto by a link. The pin-lifter is pivoted on the shaft 7, and has a slot, 8, through which 40 passes the pin 9. The rear end of the pin-lifter 6 has a rearward projection, 10, forming a stop against the flange 11 on the draw-head. The shaft of the pin-lifter has a downwardly-projecting crank, 21.

45 12 are rock-shafts provided with handles 13, and attached to the shaft of the pin-lifter by the couplings 14.

15 is a ball to support the pin when withdrawn.

50 16 is a shoulder on the lug 17 to support the arm 6.

The operation of this device is as follows:

To uncouple two cars, it being necessary to raise the pin in the draw-head of one, it is accomplished by turning the shaft 12 of the pin-lifter toward the car to which it belongs, and the pin 9 will engage with the rear end of the slot 8, and carry with it the pin-lifting arm 6 and lift the pin, which will allow the link to be withdrawn from that draw-head, when the ball 15 will roll under the pin and support it; or, if desired, the pin may be raised slightly higher until the rearwardly-projecting end 10 will stop it, when it may be pushed onto the shoulder 16, which will support the pin when 65 it is desired to push cars and not to couple them. At all other times the pin should be supported by the ball, in order that it will drop on the ball being pushed out of the way by the incoming link. To couple two cars, the 70 pin being supported by the ball in one, the link in the other is raised by turning the rock-shaft 12 away from the car to which it is attached, the slot 8 in the link-lifting arm allowing it to be so turned, which will cause the 75 downwardly-projecting crank 21 to engage with the upwardly-projecting crank 4 and carry it toward the car, which operation will raise the link to any desired height. As it is never necessary to raise the pin and link in 80 the same draw head at the same time, this plan of operating the link and pin lifter is less complicated, more easily attached to cars of any construction, and more convenient of operation than those heretofore used.

85 It is not my intention in this application to claim anything shown in my previous Letters Patent and application hereinbefore referred to; but

What I do claim as new, and desire to secure 90 by Letters Patent of the United States, is—

In a car-coupling, the combination of the draw-head 1, the link-lifter 2, pivoted by a shaft having a crank, 4, a pin-lifting arm, 6, pivoted on a shaft having a crank, 21, and the rock-shaft 12, substantially as described, and 95 for the purpose specified.

In testimony whereof I affix my signature in presence of two witnesses.

REUBEN JONES.

Witnesses:

A. P. WOOD,
LEWIS REDWINE.
